UNITED STATES PATENT OFFICE.

WILLIAM A. BARTON AND ANDREW A. DE LEWIS, OF CHATTANOOGA, TENNESSEE.

YARN-CLEANING DEVICE.

Application filed April 28, 1922. Serial No. 557,067.

To all whom it may concern:

Be it known that we, WILLIAM A. BARTON and ANDREW A. DE LEWIS, citizens of the United States, residing at Chattanooga, in the county of Hamilton and State of Tennessee, have invented certain new and useful Improvements in Yarn-Cleaning Devices; and we do declare the following to be a full, clear, and exact description of the invention, such as will enable others skilled in the art to which it appertains to make and use the same.

This invention relates to an improved yarn cleaning device for use in cleaning yarn from over-sized knots, bunched places caused by husks or by improper spinning and other obstructions. If these knots, enlargements and other obstructions which are known in the art as "slugs" are not removed, a poor grade of yarn is the result and therefore after the yarn has been spun, it is to be run from the quill onto a winding cone and while passing from this quill to the winding comb will be engaged by this cleaning device which is called a guide and the slugs will be removed. In order to remove the improperly tied knots and obstructions in the yarn, there are devices which are now in use, one of which is a simple contrivance and consists of a flat surface over which the yarn is caused to pass. This flat surface or plate extends in front of a guide and the plate may be raised or lowered so as to adjust the space between the guide and plate to the proper size to permit a thread to pass between them. A weight is placed on the plate in front of the guide and the thread passes under this weight so that it is kept under tension.

In some mills a guide of a better grade is made use of and consists of a comb of steel teeth set above a spindle bar and at such distance from the spindle bar as to permit the thread to pass over the bar and under the comb. The comb is intended to catch the knots and other obstructions that may be in the thread but which were not taken out in passing under the guide bar. When a knot of an oversize or some other obstructions attempts to pass the guide, it will catch at the bar or will catch against the teeth of the comb thus causing the yarn to break. The operator must then break out the defective portion of the yarn and after passing the thread through the guide, properly tie the broken ends of the thread together.

The objection to these guides now in use is that they either have a hole through which small knots and slugs may pass or the comb is so attached that it may be raised by simply placing a strip of paper or other material behind the comb. This work is done on a piecework basis and therefore an operator who desires as little breakage as possible will place the thread to run through the larger opening or raise the comb so as to let the knots and slugs pass. Therefore, the thread will not be properly cleaned and an inferior grade of thread will be the result. With this device, the guide bar which also constitutes the comb is so mounted that it can be readily adjusted for threads of different sizes and is moved by means of a set-screw having a countersunk head for engagement by a key which will be retained by the superintendent or other official in charge. Therefore, the guide bar cannot be tampered with by the operator and knots and other obstructions which should be removed cannot be allowed to pass through the device. It will be further noted that the thread when approaching the device will be allowed to run loose and thus permit it to have an oscillating motion which will throw the thread against the teeth of the comb and thus give a comb a better opportunity to remove any foreign matter from the thread.

This improved yarn cleaning device is illustrated in the accompanying drawings, 90 wherein:

Figure 1 is a view showing the device in side elevation and mounted for use.

Figure 2 is a top plan view of the improved device.

Figure 3 is an enlarged view showing the device in front elevation.

Figure 4 is a sectional view taken on the line 4-4 of Fig. 2.

Figure 5 is a sectional view taken along the line 5-5 of Fig. 2.

Figure 6 is a perspective view of the guide bar and comb.

This improved yarn cleaning device is provided with a base plate 1 which may be termed the body portion and is provided with a transversely extending passage 2 through which a rod 3 will extend to permit mounting of the device, a set-screw 4 being provided to engage the rod 3 and securely but releasably hold the device in the proper position upon the rod. This base plate or

body portion 1 may be rectangular in shape if desired or may be cut away as shown in Fig. 2. The rear portion through which the rod extends is thickened as shown at 5 so that the portion in which the opening 2 is formed will not be weakened. This thickened portion is provided with a threaded socket 6 which extends from the upper face of the base plate and receives the threaded lower end portion of the stem or pin 7. This stem or pin 7 extends upwardly from the base plate and has its free end portion bent to provide a side arm 7' serving as means to prevent the disk 8 which constitutes a weight from being caused to jump off of the pin. It will thus be seen that the disk or weight 8 will be permitted of free movement upon the pin but cannot become accidentally detached. Guide arms 9 extend from the forward edge of the base plate 1 and as shown in Fig. 2 extend in flaring relation to each other. It will thus be seen that the thread 10 passing from the quill 11 to a suitable winding cone may be passed between these arms 9 and permitted to have limited movement along the base plate. Therefore, this thread will engage with the combined comb and guide bar in a very efficient manner.

The guide bar 12 extends along the upper face of the base plate 1 and has one end portion provided with openings 13 to receive pins 14 carried by the base plate 1. From an inspection of Fig. 4, it will be seen that when put in place, these pins 14 are passed through openings formed in the base plate and have their upper end portions extending through the openings 13 of the guide bar 12. These pins fit tightly in the openings of the base plate so that they do not have movement relative to the base plate but are sufficiently loose in the openings 13 to permit the guide bar to be moved vertically. In order to provide means for holding the guide bar in engagement with the base plate and provide for adjustment of this bar relative to the base plate, there has been provided a screw 15 having its shank portion provided adjacent the head of the bolt with left-hand threads as shown at 16 in Fig. 4, the free end portion of the shank of this bolt being reduced and provided with right-hand threads as shown at 17. It will thus be seen that the reduced portion of the shank may be passed through the threaded opening 18 of the guide bar and the portion of the shank adjacent the head screwed into the opening 18. The reduced end portion of the bolt can then be screwed into the threaded opening 19 of the base plate. After the bolt has been put in place, the pins 14 will be inserted and the guide bar will be prevented from having rotary movement. In view of the fact that the portions 16 and 17 of this bolt are oppositely thread-

ed, turning of this bolt in one direction will move the guide bar towards the base plate and turning of the bolt in an opposite direction will move the guide bar away from the base plate. This movement however is limited due to the fact that when the bolt is turned to unscrew it from the base plate, the guide bar moves vertically away from the base plate until it contacts with the head of the bolt and prevents further rotation of the bolt. When the bolt is rotated to move the guide bar from the plate, rotation of the bolt is stopped as soon as the guide bar contacts with the upper face of the plate. It will thus be seen that the bolt cannot be entirely removed while the pins 14 are in place. By having the head of the bolt countersunk in a socket formed in the guide bar at the upper end of the threaded opening 18, the bolt cannot be turned by means of an ordinary wrench or pair of pliers. A suitable turning key will be provided which will be retained by the superintendent, foreman or other official in charge, and therefore when the guide bar is set, its position cannot be changed without permission of the official in charge. It is of course understood that if desired, the head of the bolt 15 instead of being enlarged could be reduced and provided with flat faces or could have a key receiving-socket formed in its upper end. The end portion of this guide bar which extends between the arms 9 and the weight 8 is hollowed out as shown at 21 thus providing spaced forward and rear wall portions for the bar. The front wall is shaped as shown in Fig. 5 and is cut to provide teeth as shown thus providing a comb 22. A slot 23 is formed in the base plate beneath the hollow end portion of the guide bar 12 so that when it is desired to clean the teeth of the comb, the guide bar can be moved upwardly its full extent through the medium of the screw 15 and the teeth of the comb portion thoroughly cleaned.

When this device is in use, it is set up upon the rod 3 and secured in the desired position by means of the set screw 4. The thread 10 is then passed between the arms 9 and along the base plate 1 beneath the end portion of the guide bar which has been cut to provide the comb. After being passed beneath the guide bar, the thread is passed beneath the weight and then carried over the rear edge of the base plate to a suitable winding cone. The guide bar can be set at the proper distance away from the upper face of the base plate either before or after the device is put in place upon the rod 3 and will of course be properly adjusted according to the size of thread which is to be cleaned. In view of the fact that the portion of the thread between the quill 11 and the device is not under tension, this thread will be left free to have movement between 130

the arms 9 and therefore it will have a tendency to move longitudinally of the guide bar and pass between any of the teeth. The weight is free to move about the stem 5 or pin 7 and therefore it will serve to place the portion of the thread between the device and the winding cone under the proper tension, it will not interfere with the proper feeding of the thread to the winding cone. 10 This weight cannot readily move off of the pin due to the bent portion 7' but when desired it can be easily moved off of this pin by simply being lifted upwardly and turned at the bend. When a portion of thread reaches 15 the guide bar which has not been properly tied or has become lumpy, this portion will catch in the teeth of the comb or between the guide bar and base plate and the thread will be broken. The operator will then break 20 out the imperfect portion of the thread and after feeding the thread through the guide will properly tie the broken ends together.

We claim:

1. A yarn cleaner comprising a base plate, 25 a guide bar upon the upper face of the base plate having one end portion provided along one side with comb-forming teeth, the base plate having a threaded opening formed therein and the guide bar having a threaded 30 opening registering with and larger than the opening formed in the base plate and having its threads cut in opposed relation to the threads of the opening in the base plate, a bolt screwed into the threaded opening of 35 the guide bar and having a reduced and oppositely threaded portion screwed into the threaded opening of the base plate, and pins

passed up through the base plate into openings in the guide bar upon opposite sides of 40 the bolt.

2. A yarn cleaner comprising a base plate, a guide bar upon the upper face of the base plate having one end portion provided along one side with comb-forming teeth, the other end portion of the guide bar being provided with a threaded opening, means for vertically adjusting said guide bar rotatably carried by said base plate and having a threaded portion extending through the threaded 45 opening of said guide bar for imparting vertical movement to the guide bar when rotated, said means including means for engaging said guide bar and limiting upward movement of the guide bar, and means for preventing rotation of said guide bar when 50 said adjusting means is rotated.

3. A yarn cleaner comprising a base plate, a guide bar upon the upper face of the base plate having one end portion provided along one side with comb-forming teeth, a bolt 55 screwed into a threaded opening formed in the other end portion of the guide bar and beneath the guide bar reduced and oppositely threaded and screwed into a correspondingly threaded opening in the base 60 plate, and means carried by the base plate and engaging the guide bar to permit vertical movement and prevent turning movement thereof.

In testimony whereof we have hereunto 70 set our hands.

WILLIAM A. BARTON.
ANDREW A. DE LEWIS.
